UNITED STATES PATENT OFFICE.

KARL VÖLLER, OF DUSSELDORF, GERMANY, ASSIGNOR TO RHEINISCHE METALL-WAAREN- UND MASCHINENFABRIK, OF DUSSELDORF-DERENDORF, GERMANY, A CORPORATION OF GERMANY.

AMMUNITION-WAGON.

1,088,047.

Specification of Letters Patent. Patented Feb. 24, 1914.

Application filed February 14, 1910. Serial No. 543,715.

To all whom it may concern:

Be it known that I, KARL VÖLLER, engineer, a subject of the German Emperor, residing at 17 Jülicherstrasse, Dusseldorf, 5 Germany, have invented new and useful Improvements in Ammunition-Wagons, of which the following is a specification.

This invention relates to an ammunition wagon which is especially suitable for 10 mount batteries, when the ammunition has to be carried after the guns over trackless and difficult country.

According to the invention the ammunition wagon can be separated into a series of 15 parts which can be packed on animals for transport, so that, where it is absolutely impossible to use the wagon as a wheeled vehicle, this mode of transport can be adopted until the ground is more suitable. The 20 wagon can then be easily and quickly put together again.

One construction according to the invention is shown in the accompanying drawings.

Figure 1 is a side elevation of the wagon, 25 Fig. 2 is a rear view, and Figs. 3, 4 and 5 are detail views.

On the wheel axle *a* two longitudinal beams *b* are mounted and duly struttied. The connection between wheel axle and 30 beams is made elastic by intermediate rubber buffers *x* or other springs, so as to prevent shocks during travel from being transmitted in full to the ammunition. These beams *b* are made in parts hinged together 35 as at *d* and held extended in line by suitable bolts or the like such as *c*; by loosening the latter the beam can be folded. The position of the hinge is such that the length of the folded beam is a suitable package for the 40 beast of burden.

Above the beams *b* is a box frame *e* made in two parts, the bottom *f'* of which is of armor plate. The box frame *e* is made in two parts in order that it may be easily 45 packed; the parts are connected with the beams by engagement of slotted projections *f* on the frame in corresponding eyes *g* fixed to the beams *b*, and by clips *h* on the framework which grip the beams and are rigidly 50 connected therewith by bolts *i*.

When the wagon is tipped into the position indicated by line A—B in Fig. 1, the armored bottom serves to protect the men against the enemy's fire. For the same pur-

pose, at the sides of the box frame *e* shields 55 *k* can be pivoted (see Fig. 2) which, when in use, lie parallel to the bottom *f'* of the box, but when traveling are turned up. The box frame *e* has on the upper surfaces of its sides a series of straps *m*, in which the 60 handles *n* of the steel shot cases *o* standing on the bottom *f'* of the box are engaged. The position of each shot case *o* is fixed by covering its top with one or more caps *p* conforming with the shape of the case. 65 These caps *p* are carried by spring pins on angle iron arms or frames *q*, *r* pivoted to the box frame *e* and pressed on to the shot cases by suitable devices so as to keep the cases in position. In the example shown, for 70 this purpose a rod *s* is pivoted at the center of the box frame *e* and has pivoted at its upper end a lever *t* with cam surfaces *u*. On pulling over the lever *t* the cams *u* press on corresponding tongues *v* of the cross-bar *w* 75 connecting the pair of arms *q* and in this manner press the arms *q* together with the caps *p* tightly on to the shot cases. The ends of arms *r* engage the ends of arms *q* and so the caps *p* carried by arms *r* are simultaneously pressed on the shot cases. 80

Having now particularly described and ascertained the nature of my said invention and in what manner the same is to be performed, I declare that what I claim is:— 85

1. A knock-down ammunition wagon, comprising wheels and an axle, a pair of longitudinal beams on said axle, each beam being made in parts hinged together and provided with means for rigidly connecting said parts 90 when extended, a bed detachably mounted on said longitudinal beams, and means for securing ammunition on said bed.

2. A knock-down ammunition wagon, comprising wheels and an axle in combination 95 with a pair of longitudinal beams, a two-part bed mounted on said beams, means for detachably securing said two parts of the bed to said beams, a plurality of ammunition cases arranged on said bed, and means 100 for locking each case to the bed.

3. In an ammunition wagon, the combination, with a knock-down vehicle having a bed, of a plurality of ammunition cases each provided with carrying handles, means on 105 the bed for engaging the handles of each case to hold the case against displacement, and means for locking each case to the bed.

4. An ammunition wagon comprising a pair of wheels and an axle, in combination with a two-part bed having its bottom of armor plate, means for detachably mounting said bed on said wheels and axle, a plurality of ammunition cases mounted on said bed, and means for locking the cases in place on the bed. 35
5. In an ammunition wagon for transporting ammunition the combination of longitudinal beams made in parts hinged together, means for rigidly connecting said parts with each other in extension, a box for carrying the ammunition, shot cases arranged within said box, and means for pressing the shot cases against the bottom of the box, substantially as described and for the purpose set forth. 40
- 10 6. In an ammunition wagon for transporting ammunition the combination of longitudinal beams made in parts hinged together, means for rigidly connecting said parts with each other in extension, a box for carrying the ammunition, shot cases arranged within said box, elastic caps and means for pressing the shot cases against the bottom of the box, substantially as described and for the purpose set forth. 45
- 15 7. In an ammunition wagon for transporting ammunition the combination of longitudinal beams made in parts hinged together, means for rigidly connecting said
- 20 25 30
- parts with each other in extension, a box for carrying the ammunition, shot cases arranged within said box, elastic caps and means for pressing the shot cases against the bottom of the box, substantially as described and for the purpose set forth. 50
- 35 40 45 50 55
8. In a knock-down ammunition wagon the combination with wheels and an axle of longitudinal beams made in parts hinged together, means for rigidly connecting said parts with each other in extension, a two part bed for carrying the ammunition, removable means for rigidly connecting the parts of the bed with the beams and a plurality of shot cases removably attached on said bed.
9. A knock-down ammunition wagon comprising a pair of wheels and an axle, in combination with a two-part bed having its bottom of armor plate, means for detachably mounting said bed on said wheels and axle, and means for carrying ammunition on said bed, said bed adapted to be tilted to an inclined position to form an armor shield.
- In testimony whereof I have signed my name to this specification in the presence of two subscribing witnesses.

KARL VÖLLER.
